(57) **CLAIM**

The ornamental design for a plate grip, as shown and described.

DESCRIPTION

FIG. 1 is a top view of the plate grip of the present invention, showing the new design;

FIG. 2 is a bottom view of the plate grip of FIG. 1;

FIG. 3 is a first side view of the plate grip of FIG. 1;

FIG. 4 is a second side view of the plate grip of FIG. 1;

FIG. 5 is a back view of the plate grip of FIG. 1;

FIG. 6 is a cross section view of the plate grip at line 6-6 of FIG. 1;

FIG. 7 is a cross section view of the plate grip at line 7-7 of FIG. 1;

FIG. 8 is a bottom perspective view of the plate grip of FIG. 1;

FIG. 9 is a side perspective view of the plate grip of FIG. 1;

and,

FIG. 10 is a bottom perspective view of the plate grip of FIG. 1.

The evenly spaced broken lines depict portions of the plate grip that form no part of the claimed design.

1 Claim, 8 Drawing Sheets
